UNITED STATES PATENT OFFICE.

WILLIAM H. BEERY, OF CELINA, OHIO.

CULVERT-MOLD.

1,043,193.

Specification of Letters Patent.

Patented Nov. 5, 1912.

Application filed March 29, 1911. Serial No. 617,731.

To all whom it may concern.

Be it known that I, WILLIAM H. BEERY, a citizen of the United States, residing at Celina, in the county of Mercer and State of Ohio, have invented a new and useful Culvert-Mold, of which the following is a specification.

It is the object of this invention to provide a mold for the fashioning of concrete structures, the construction of the mold being such that certain constituent parts thereof, remain in the completed structure, to serve as reinforcing elements therefor.

In this specification, I shall describe the mold as being employed for the formation of a culvert, the word "culvert" being employed in a loose and generic sense to indicate a fluid conducting element of any sort.

A further object of the invention is to provide a culvert mold, parts of which are adapted to remain in the completed culvert, to serve as reinforcing elements therefor, the said parts being provided with means whereby the inner and outer laggings of the culvert may be removably held in place during the construction of the culvert.

With the foregoing and other objects in view which will appear as the description proceeds, the invention resides in the combination and arrangement of parts and in the details of construction hereinafter described and claimed, it being understood that changes in the precise embodiment of invention herein disclosed can be made within the scope of what is claimed without departing from the spirit of the invention.

In the accompanying drawings.—Figure 1 is a side elevation, parts being broken away; Fig. 2 is a transverse section; Fig. 3 is a perspective of one form of the completed product of the mold.

The device forming the subject matter of this application, is adapted to be employed in fashioning culverts, of the sort commonly used in providing in a passageway for streams beneath highways and the like.

In carrying out the invention, a trench is first dug, in the line in which the culvert is to extend. If desired, a bed of concrete or the like, denoted by the numeral 1, may be fashioned in the trench, longitudinally of the same. Upon this bed 1, when the same is used, a plurality of supports 2 are placed, the supports 2 being spaced apart, longitudinally of the trench.

Each of the supports 2 consists of inner and outer circumferentially continuous members, the inner member being ordinarily a ring 3, and the outer member being ordinarily a ring 4, of considerably larger diameter than the ring 3. These rings 3 and 4 are united by radial connections, the same being ordinarily in the form of bolts or bars, shown at 5. A plurality of securing devices, ordinarily threaded bolts or studs 6, project outwardly from the outer rings 4. Other securing devices, ordinarily threaded bolts or studs, as aforesaid, project inwardly from the inner rings 3, as shown at 7.

In the interior of the inner ring 3, a lagging 8, consisting of a plurality of sections, is disposed. Another lagging 9, likewise composed of a plurality of sections, is disposed upon the outside of the outer rings 4. The securing members 6 and 7 extend through the laggings 9 and 8, respectively, and nuts 10 are mounted upon the members 6 and 7, to hold the laggings in place.

In practical operation, the supports 2 are spaced a sufficient distance apart, so that they will form the ends of each section of culvert. Beginning adjacent the bottom of the trench successive sections of the laggings 8 and 9 are mounted in place, the concrete 15 being inserted between the laggings, as the laggings are built up. Or, if desired, the entire lagging 8 may be secured to the inner ring 3, successive sections of the outer lagging 9 being secured to the outer ring 4, until the top of the culvert is reached. During the building up of the culvert, longitudinal reinforcing bars 12 are placed upon the connections 5 between the rings 3 and 4. After the concrete has set sufficiently, the nuts 10 are removed from the members 6 and 7, permitting the laggings 8 and 9 to be removed. When it is desired to leave the flow-line of the culvert smooth, the operator may pass within the culvert, and knock off with a cold chisel or the like, inwardly projecting ends of the securing lugs 7. In a similar manner, the protruding ends of the bolts 6 may be cut off; although the cutting off of the elements 6 is a matter of minor consequence, since these elements do not protrude into the flow-line of the structure.

It will be seen that the connections 5 between the rings 3 and 4, together with the reinforcing bars 12, are inserted in the con-

stituent material 15 of the culvert, the ring 4 surrounding the outside of the finished culvert, and the ring 3 extending about the interior of the finished culvert.

5 Referring to Fig. 3, it will be seen that the finished product consists of a hollow body 14, surrounded upon the outside, at its ends, by the bands 4, and supported internally, adjacent its ends, by the bands 3, 10 the body 14 being braced transversely by the connections 5, and being braced longitudinally, by the rods 12.

From the foregoing it will be seen that a culvert, of any cross sectional contour, may 15 be rapidly built up, in any desired lengths, certain of the constituent elements of the mold, in which the culvert is fashioned, remaining in the finished product, to serve as reinforcing elements therefor.

20 In Fig. 1, the outer lagging 9 is shown as terminating adjacent the sides of the bed 1, it being presupposed that it is desired to form the bed 1 and the culvert proper 15 as one monolithic structure. It will be 25 clearly understood, however, without specific illustration, that the outer lagging 9 may be carried entirely around the circumference of the outer ring 4, whereupon the tubular structure, denoted specifically by the number 30 14 in Fig. 3, will be fashioned.

Having thus described the invention, what is claimed is:—

In a device for molding a pipe, spaced inner and outer rings; securing elements upon the outer ring, projecting away from the axis of the outer ring; securing elements upon the inner ring, projecting toward the axis of the inner ring; a lagging located upon the outside of the outer ring and removably carried by the securing elements of the outer ring; a lagging located upon the inside of the inner ring and removably carried by the securing elements of the inner ring; connections between the inner and outer rings, said connections being adapted to be embedded in the material which is placed between the laggings; and removable means upon the securing elements for engaging the laggings; the securing elements of the inner ring being severable adjacent said ring, to leave the flow line of the pipe unencumbered.

In testimony that I claim the foregoing as my own, I have hereto affixed my signature in the presence of two witnesses.

WILLIAM H. BEERY.
